UNITED STATES PATENT OFFICE.

HARRY PFANNENSTIEHL, OF EAST ORANGE, NEW JERSEY, ASSIGNOR TO WESTERN ELECTRIC COMPANY, INCORPORATED, OF NEW YORK, N. Y., A CORPORATION OF NEW YORK.

PRINTING TELEGRAPHY.

1,374,606.

Specification of Letters Patent. Patented Apr. 12, 1921.

Application filed June 8, 1917. Serial No. 173,546.

To all whom it may concern:

Be it known that I, HARRY PFANNENSTIEHL, a citizen of the United States, residing at East Orange, in the county of Essex and State of New Jersey, have invented certain new and useful Improvements in Printing Telegraphy, of which the following is a full, clear, concise, and exact description.

10 This invention relates to printing telegraphy and more particularly to an improved type of printing telegraph receiving apparatus wherein the printing of characters and various other operations are performed by 15 power-driven mechanism controlled by line current impulses.

One of the principal objects of this invention is to provide a telegraph receiver of the above class wherein all the necessary 20 functions are performed in a reliable and efficient manner at a high rate of speed.

Another object is the provision of means whereby the printing of one character may be effected simultaneously with the selection 25 of the next succeeding character.

A further object is to provide a receiving printer of the above class, suitable for printing messages in page form and one which is capable of providing a plurality of duplicate copies.

A still further object is the provision of means whereby the power mechanism for operating the printer may operate intermittently and only when signaling impulses are 35 being received.

To the above ends, means are provided for distributing a series of current impulses to a plurality of selecting and operation controlling magnets, which magnets control the 40 selection of the desired character to be printed and operation to be performed. The invention disclosed in the accompanying drawings embodies a telegraph receiving printer comprising stationary selecting mechanism, 45 a stationary paper platen, and printing elements adapted to be moved transversely of the printer. The printing mechanism disclosed is of standard typewriter construction and, in fact, the invention is applicable 50 to any suitable typewriting mechanism of the type bar sort.

Various mechanical functions, such, for example, as line spacing, carriage return, shift and unshift, automatic signaling, etc., are controlled by a plurality of special code 55 bars selectively controlled by line current impulses. The various mechanical operations of the printer are performed by a battery of rotating cams coöperating with bell crank levers or suitable operative members 60 to effect the desired operation. The cam members are mounted on a rotatable shaft to which power may be imparted by means of a motor, or any suitable driving mechanism. One of the essential features of this 65 invention is the timing of the various operations performed by the rotating cams.

The selecting mechanism consists of a plurality of stationary selecting magnets and a corresponding number of horizontal selecting bars controlled by said magnets. The selecting bars extend entirely across the printer and are adapted to be raised and lowered but are not arranged to be moved endwise.

75 A plurality of notched code bars or permutation bars are provided, and the arrangement of these bars, with respect to the selecting bars, is such that when any combination is set up by the selecting magnets 80 only one of the code bars will be permitted to move forward and mesh with the selecting bars. Each of the code bars controls a pull bar which is adapted to be moved forward by a code bar, when selected, into the 85 path of a reciprocating printing bar, which printing bar is preferably controlled by the rotating cam shaft. When a pull bar is moved forward and engaged by the printing bar, a type face carried by the selected type 90 lever is thrust against the paper platen and the selected character printed. The selecting and printing operations are so timed that, while one character is being printed, the next succeeding character may be selected 95 so that there is no time lost between the selecting and printing operations.

The above and other features of this invention will be fully set forth in the following description and claims and will be 100 more readily understood by reference to the accompanying drawings, in which Figure 1

is a perspective view of the mechanism as assembled, with certain parts broken away to more clearly show the coöperation between the selecting mechanism and the movable type carriage, and between the various stationary and movable parts; Fig. 2 is a vertical sectional view taken just to the right of the center of Fig. 1 with the movable type carriage in the center; Fig. 3 is a vertical sectional view through the special selecting mechanism at the left-hand side of Fig. 1; Fig. 4 is a plan view of a portion of the selecting mechanism shown in the front of Fig. 1; Fig. 5 is a detail view of the driving and brake mechanism; Fig. 6 is a vertical sectional view on line 6—6 of Fig. 5; and Fig. 7 is a detail view of a one-way clutch taken on line 7—7, Fig. 5.

The mechanism herein disclosed is operated preferably by various combinations of five positive and negative selecting impulses, with an additional impulse following each group of selecting impulses for starting the mechanism in operation. The impulses may arrive over a line from a distant station and may be distributed to the selecting and starting magnets by means of a Baudot distributor, or any other of the well known distributing systems.

In order to simplify the drawings a considerable portion of the frame structure has been omitted. Also various springs, which would normally be used for restoring various operating parts to normal, have been omitted so as to avoid complicating the drawings. It is to be understood, however, that suitable supporting means may be provided for the selecting and driving mechanism and that springs may be provided wherever necessary for assisting in the operation of parts or restoring the various parts to normal.

In the construction of the printer, the preferred embodiment of which is disclosed in the accompanying drawings, some very radical departures have been made from type-bar printers heretofore developed. In the accompanying drawings is shown a stationary paper platen, a movable type carriage, and means for selectively operating the desired type carried by the movable type carriage. The movable type carriage, including the type levers, bell crank levers, code bars, universal printing bar, etc., is adapted to be moved from left to right, transversely of the machine against the tension of a spring, one character space for each revolution of the cam shaft, and is adapted to be released, and returned to its initial position by the said spring, for commencing a new line. The cam shaft, which performs all the mechanical operations, is constantly under spring tension, tending to rotate. Power for rotating the shaft is stored up in a spring by means of a motor, the circuit for which is

controlled by a traveling member carried by the cam shaft. A brake-band coöperates with a cam carried by the cam shaft for stopping and holding the shaft against rotation, the cam surface being so shaped as to bring the shaft to a positive stop without shock or jar to the operating parts. For releasing the cam shaft to start the printer in action, a starting magnet is provided for operating a trip, comprising a toggle-joint and a series of levers which provide slack in the brake-band and permit the shaft to make one complete revolution when it is again gripped by the band and held until the starting magnet is again energized.

Referring to the drawings, and particularly to Fig. 1, the invention is illustrated in combination with a type carriage of a form so well known as to require no detailed description. The type carriage 10 carrying the type bars, connecting links, code bars, etc., is supported by a portion of the frame 12 and rotatable shaft 14.

The selecting mechanism consists of five selecting magnets 15, 16, 17, 18 and 19 (only four of which are shown in Fig. 1), five horizontal selecting bars 20, 21, 22, 23 and 24 extending entirely across the printer at right angles to the code bars, and five latches 25, 26, 27, 28 and 29 extending from the armatures of the selecting magnets, to the selecting bars. The selecting bars are normally held in the position shown by the latches 25 to 29 inclusive and the notched members 11, and when released and permitted to drop they are held in their lowered positions by means of springs 13, until restored by the upward movement of the members 11.

Another feature of the selecting mechanism is an overlap arrangement best shown in Fig. 4 comprising an overlap magnet 30, armature 31 and locking members 32. The operation of this mechanism will be described later. It may be stated here, however, that the overlap magnet and a starting magnet 33, which may be connected either in series or in parallel, are operated by a sixth impulse, or an impulse following the five selecting impulses. Or they may be connected in independent circuits and the overlap magnet may be controlled by a contact actuated by a cam on the cam shaft.

Selecting and printing.

A better understanding of the apparatus may be obtained from a description of a particular type selection and the various operations incident thereto.

Assume that the sending apparatus at a distant station is transmitting a series of impulses for selecting the character D, and further assume that the character D is selected by five impulses combined in the following order: positive, negative, negative, 130

positive, negative. Let us also assume that at the receiving station there is a polarized line relay which responds to only positive impulses, and which controls the energizing circuits of the selecting magnets 15, 16, 17, 18 and 19. Then since the first and fourth impulses are of positive polarity current will be supplied to the selecting magnets 15 and 18, and since the second, third and fifth impulses are of negative polarity no current will be supplied to selecting magnets 16, 17 and 19. Consequently only selecting magnets 15 and 18 are energized. Selecting magnets 15 and 18 when energized attract their armatures and withdraw their respective latches 25 and 28 from engagement with the corresponding selecting bars 20 and 23. The selecting bars 20 and 23, however, do not fall the instant the latches are withdrawn because the bars are supported by the members 11—11 which are controlled by the power-driven cam shaft. The five selecting impulses have now been received, the selecting magnets 15 and 18 have been energized and selecting bars 20 and 23 have been conditioned for action awaiting receipt of the sixth or starting impulse. The sixth impulse effects the energization of the overlap magnet 30 and the starting magnet 33. The energization of the starting magnet 33 causes the release of the brake-band 34 (which action will be more fully described hereinafter), and permits the cam shaft 48 to start rotating. The instant after the cam shaft starts to rotate in the direction of the arrow (Fig. 3), the vertical plungers 35—35 are permitted to rise, due to the shape of the cam surfaces 36—36 and the springs connected to the rockable arms 37—37, and consequently the members 11—11 responding to the movement of the rockable arms 37—37, are pulled down by suitable springs until the extensions 38—38, carried thereby, engage the adjustable stops 39—39. Since only the selecting bars 20 and 23 have been conditioned for movement by the withdrawal of the latches only these bars will be permitted to follow the downward movement of the notched members 11—11, the extent of their downward movement being determined by the stops 39—39.

The selecting bars have now been arranged to permit one and only one of the code bars 40 to move forward, when released, astride the selecting bars. The code bars 40 are normally held in the position shown by the universal bar 41, which extends entirely across the type carriage in front of the extensions 42, carried by the bars 40, the forward pull of the springs 43 being insufficient to counteract and overcome the pull of springs 44.

The universal bar 41 and the printer bar 45 are moved out of their normal positions by means of a striker bar 46, which

is forced downwardly by the action of cams 47—47 on cam shaft 48. The striker bar 46 is carried by two bracket arms 49 and 50, which are pivotally secured to a supporting rod 51. The rod 51 may be journaled in the sides of the printer frame or it may be supported in any suitable manner. The bar 46 may be normally held in the position shown, by suitable springs. On each of the bracket arms 49 and 50 is secured an adjustable member 52, one of which is clearly shown in Fig. 2. On the supporting rod 51 and adjacent each of the bracket arms 49 and 50 is pivotally mounted an arm 53, which arms are adapted to be engaged and operated by the cams 47—47. Each of the arms 53 carries a member 54 which is normally held in engagement with its corresponding adjustable member 52, by a spring 55, but may be held away from the members 52 for certain purposes as will presently appear.

It will be seen by reference particularly to Figs. 1 and 2 that when the cam surfaces 47—47 force the arms 53—53 forward, the striker bar 46 will be forced downward and by acting on the extensions 56 and 57 of bell crank levers 58 and arms 59, the universal bar 41 will be moved forward and the printing bar 45 will be moved upward. All of the code bars are normally held clear of the selecting bars by the universal bar 41 and when the universal bar is moved forward all of the code bars, due to the action of the springs 43, will also move forward slightly, but only the selected code bar will be permitted to move forward astride the selecting bars. As the selected code bar moves forward the extension 60 thereof engages a pin 61 on the corresponding pull bar 62 and moves its respective pull bar into the path of the reciprocating printing bar 45, so that on its downward stroke the printing bar strikes the end of the selected pull bar 62, and by means of a lever 63 connecting each of the pull bars with its corresponding type bar 65 the desired type is thrust against the paper platen in a well-known manner.

By reference to Fig. 2 it will be readily understood that in view of the pitch of cams 47—47 and the high rate of speed of the cam shaft, which speed may be assumed to be at least 600 R. P. M., the downward movement of the striker bar 46 is very rapid and consequently the forward and upward movements of the bars 41 and 45 respectively, are equally rapid. By a proper selection of springs 44 and 64 these bars may be returned to normal with equal rapidity and, in fact, it is desirable that the springs 64 be of such strength that the printing bar will strike the selected pull bar with such force that the pull bar will travel ahead and disengage itself from the printing bar and permit the springs 66 to return the

actuated pull bar to normal position as the selected code bar is restored by the universal bar 41 under the action of springs 44. The quick action of the printing bar causes the 5 selected type bar to be thrown against the paper platen with sufficient force for mani- folding and may also be sufficient to cause the type bar to return to normal due to rebound, or the return action of the type 10 bar may be increased by providing a spring, such as 67, connected to each of the connect- ing links 63.

The function of the code bars is to move the pull bar, corresponding to the character 15 selected, into the path of the reciprocating printing bar 45. Therefore, as soon as a particular pull bar has been engaged by the printing bar, the selected code bar should be withdrawn so that the selecting bars may be 20 restored and a new selection set up. The springs 44 should, therefore, be of such strength as to restore the universal bar 41 the instant the printing bar engages the selected pull bar. Immediately after the se- 25 lected code bar is withdrawn by the universal bar 41, the cams 36—36, acting upon the plungers 35—35, rock the members 37—37 and raise the members 11—11 to restore the selecting bars to normal, ready for a new 30 selection.

Spacing.

Spacing between characters is effected by the cam shaft, and in the embodiment dis- 35 closed, the type carriage is moved forward one step, or one character space, immediately after each character is printed. A pivotally mounted rod 75 is provided which may be journaled in the frame of the printer 40 or supported in any suitable manner. Rig- idly secured to the rod 75 are two bracket arms 76 (only one of which is clearly shown), which carry the rack 77. To the free end of the operating lever 78 is con- 45 nected an arm 79 on the end of which is a pawl 80, adapted to engage the teeth of the ratchet 81 whenever the arm 79 is moved forward by the action of the cam 82 acting on the arm 78. The arm 78 is provided with 50 a spring 83 (Fig. 3), for operating the pawl and ratchet when the arm 78 is permitted to return. The rotation of the ratchet 81 effects the rotation of the shaft 14, and by means of the worm-wheel 84 mounted there- 55 on and coöperating with the rack 77, the type carriage 10 is moved to the right one step, or one character space, for each revolution of the cam shaft.

The spacing mechanism is so arranged 60 that the type carriage will be stepped ahead immediately after a character is printed, although obviously, spacing may be effected, if desired, before the printing of each character.

65 When it is desired to space between words,

the spacing is effected in the manner above described, but the selecting mechanism is not actuated to permit printing of a character, that is, the first five selecting impulses are such that no code bar is selected and conse- 70 quently no pull bar will be permitted to move into the path of the reciprocating printing bar.

Visible typewriting.

The cam 82, in addition to controlling the spacing between characters and words, also controls the position of the inking ribbon 85 which is normally in the position shown in Fig. 1. When the arm 79 is moved for- 80 ward, as already explained, the extension 86 engages the crank arm 87. As will be clearly understood by reference to Figs. 1 and 3, the rotation of the rod 88 and bracket arms 89 and 90 acting upon the pins 91 and 92 cause the ribbon 85 to be moved in front of the type bar just as it strikes against the paper platen. The springs 93 and 94, acting on the pins 91 and 92, serve to hold the ribbon down from in front of the printed char- 85 90 acters so that they are visible at all times except at the instant a character is printed.

Any suitable ribbon feeding mechanism may be provided for feeding the ribbon transversely of the machine.

Overlap arrangement.

As already stated, the overlap magnet 30 may always be operated by an impulse fol- 100 lowing the five selecting impulses. The function of the overlap magnet, together with the locking mechanism is to make possible the selection of a new character while the preceding character selected is being printed. Each of the latches 25 to 29 in- 105 clusive, is provided with an extension 68, (Fig. 4) so placed that when a selecting magnet is energized to withdraw its re- 110 spective latch from under its corresponding selecting bar the extension 68 will be en- gaged by a stop 69, carried by each of the members 32, and the latches corresponding to the actuated selecting magnets will be held in their moved positions until the mag- 115 net 30 attracts its armature 31 and with- draws the stop 69 from engagement with the extensions 68 on the moved latches. As soon as the latches are unlocked by the ac- 120 tuation of magnet 30, they will be returned by the action of springs 70, connected to the armatures of the selecting magnets, until the bent over portions 71 (Fig. 2) abut against the selected bars, in which position the latches will be held until the selected 125 bars are restored to normal, thereby per- mitting the latches to move in under the restored bars, providing a succeeding se- 130 lection does not interfere with the complete return of the latches. If, however, a suc- ceeding selection coming before the selected

bars are restored, utilizes one or more positive impulses corresponding in order to those of the preceding selection, then the latches will be again actuated by their respective magnets, and will be locked in their actuated positions until the overlap magnet is again energized. The operation of magnet 30 should take place, preferably, immediately after the selected bars are actuated so that the released latches may abut against the selected bars and be in position to respond to the next selection, if required, or to move under the bars the instant they are restored to normal, if they are not required for the next selection. By means of this arrangement a new selection may be set up while the preceding character selected is being printed. Thus, it will be seen that the function of the latches and overlap magnet is two-fold,—first, by locking the latches in their actuated position until the selected bars are lowered, by the action of the cam shaft, they are thereby prevented from returning and interfering with the downward movement of the selected bars; and, secondly, by releasing the latches as soon as the selected bars are lowered, they are placed in readiness to move in under the selected bars the instant they are restored, or they may again be selected and locked up without moving under the bars, providing the succeeding group of selecting impulses has positive impulses in common with those of the preceding group. This feature when combined with a type-bar printer which has an inherent overlap in itself, permits an exceptionally high rate of speed to be attained, much higher in fact than can be attained with a printer of the type-wheel sort.

Driving mechanism.

Referring to Figs. 5, 6 and 7, the cam shaft 48 is normally tending to rotate under the action of a driving spring 95, but is adapted to be held against rotation by means of a brake-band 34, the tension of which is controlled by a starting magnet 33, and a series of levers. When the starting magnet 33 is energized by the sixth or starting impulse it attracts its armature 96 and moves the toggle-joint 97 in the direction of the arrow A about the pivotal point 98. This causes the lever 99, which is bifurcated at one end, to move in the direction of arrow B about the fulcrum points 100 which rest against the cam surfaces 110 and 111, and consequently loosens the brake-band 34, thereby permitting the cam shaft 48 to rotate and perform its functions. The cam shaft, in addition to performing the various operations incident to selecting and printing, which have already been described, also controls means for storing up power in the driving spring 95 and cooperates with suit-

able mechanism for overcoming the power of the driving spring to bring the shaft to rest.

In Fig. 5 is shown the motor 101, driving shaft 102 and pinion 103 carried thereby, 70 coöperating with the gear 104 for winding up the spring 95. On the shaft 48 is a key 105 coöperating with a nut 106 threaded on a sleeve 107. Contacts 108 and 109 control the series field of the motor 101 and are 75 adapted to be closed upon the rotation of the cam shaft, by the movement of the traveling nut 106 toward the key 105. As soon as these contacts are closed the circuit through the motor will be completed, and the motor will start and again wind up the spring 95 a predetermined amount, ready 80 for the next revolution of the cam shaft. The action of the motor on the gear 104 and sleeve 107 causes the nut 106 to travel in 85 the opposite direction or away from the key 105 and open the circuit of the motor by breaking of contacts 108 and 109. Thus it will be seen that power is automatically 90 and intermittently stored up in the spring 95 for operating the cam shaft 48.

When the field circuit of the motor 101 is closed the shaft 102 rotates in the direction of the arrow and stores up energy in the spring 95. To prevent the spring 95 from 95 rotating the shaft 102 in the opposite direction when the field circuit of the motor is open a one-way clutch (Fig. 7) is provided. The clutch comprises balls or rollers 175 which are held in the position shown by 100 yielding springs 176. The rollers 175 permit the motor shaft 102 to rotate in the direction of the arrow and prevent the shaft from rotating in the opposite direction due to the friction set up between the rollers and the shaft and between the rollers and frame 177.

When the lever 99 starts moving in the direction of arrow —B— about pivotal points 100, it will continue its movement in 110 that direction until the adjustable nut 193 carried by the stop screw 192, abuts against the frame 12, whereupon the pivotal point of lever 99 will be transferred from 100 to 194. Then as the cam shaft rotates and the 115 bifurcated end of lever 99 rides down on the low portion of cams 110 and 111, the spring 113 will return the toggle-joint 97 and joint 114 to normal, thereby again transferring the pivotal point of lever 99 from 194 to 120 114. Now as the cam shaft continues to rotate and the bifurcated end of lever 99 rides up on the cam surfaces 110 and 111 it will readily be seen that the lever 99 will be rotated about the pivotal point 114 and the 125 brake-band 34 will be caused to grip the drum 115 and stop the rotation of the cam shaft 48.

If desired, a strip of felt, canvas or any suitable material may be placed between the 130

brake-band and drum 115 to reduce slippage and insure positive action of the brake-band.

Auxiliary selections.

- 5 In addition to selecting and printing various characters and providing means for spacing between characters and words, as hereinbefore described, there are various mechanical operations to be performed,
 10 such, for example as carriage return, line spacing or paper feed, shift and unshift (that is shifting from lower case to upper and vice versa), automatic signaling, etc.
 15 To the left-hand side of Fig. 1 is shown a plurality of special code bars 121, 122, 123, 124 and 125, which are similar to the code bars 40 mounted on the movable type carriage 10. The special code bars are adapted to slide in recesses provided in stationary
 20 supports 126 and 127 and are selectively controlled by line current impulses in the same manner as character code bars 40. That is, the various mechanical functions are selectively controlled by code signals which are
 25 transmitted in the same manner and by the same means as the various character signals. Also the power for performing the various mechanical functions is supplied by the rotary cam shaft, as hereinbefore de-
 30 scribed in connection with character printing.

Type carriage return.

Mention has already been made of the manner in which the type carriage is moved from left to right step by step for line printing. When it is desired to return the type carriage to the left to commence a new line a group of impulses is sent over the line to cause the selecting mechanism to select the
 40 special code bar 125, which group of selecting impulses is followed by a sixth or starting impulse as usual, for releasing the cam shaft. Now when the cam shaft starts rotating, the cam 128 acting upon the bell
 45 crank lever 129 will force the auxiliary striker bar 130 (which bar corresponds to the main striker bar 46) down against the action of suitable springs (not shown). The bar 130 acting upon the bell crank levers
 50 131 and 132 will move the auxiliary universal bar 133 (which bar corresponds to the main universal bar 41) forward and permit the selected special code bar 125 to move forward astride the selecting bars 20 to 24
 55 inclusive. As the bar 125 moves forward under the action of suitable springs it moves a pull bar 134 forward in the path of a reciprocating member 135 carried by a bell crank lever 136, which is operated by a cam
 60 on the cam shaft 48. The pull bar 134 is connected to the rack 77 and when the rack is pulled down by the action of the pull bar, the rack is disconnected from the worm wheel 84 and is temporarily locked down by

the locking disk member 138 carried by shaft 14. The member 138 is normally held against the end of the rack 77 by a spring 139, as shown in Fig. 1, and when the rack is depressed, the member 138 under the action of spring 139, engages the off-set portion 140 and holds the rack in its depressed position until the type carriage is completely returned by the action of a suitable spring and tape 141, whereupon, the member 142 carried by the type carriage engages the disk 138, forcing it back against the action of spring 139, thereby permitting the rack 77 to return to normal and engage the worm-wheel 184.

It is preferable that, when the type carriage is being returned ready for commencing a new line, there shall be no unnecessary friction between the stationary and movable parts. Therefore, it is desirable that means be provided to prevent operation 85 of the striker bar 46 while the type carriage is being returned. This is accomplished by providing two arms 190 rigidly secured to the rod 75, so that, when the rack 77 is depressed and the rod 75 rotated, the arms 90 190 will act upon the members 54 and hold them out of engagement with the members 52, thereby preventing actuation of the striker bar 46 until the type carriage has been returned and the rack 77 has been released.

Line feed.

For the purpose of rotating the paper platen 145 to feed the paper and space between lines a special code bar 124 is provided, which co-operates with a pull bar 146 and cam 147 for operating the ratchet 148. When the bar 124 is selected and permitted to move forward it acts upon the pivotally supported member 149 and moves the pull bar 146 in the path of the reciprocating member 150 carried by the bell crank lever 151, which is operated by the cam 147. When the pull bar is pulled downwardly it 110 operates the pawl 155 and ratchet 148 through the connecting bell crank lever 152, connecting link 153 and arm 154. The cam surface 156 may be adjusted by the handle 157 for determining the extent of rotation 115 of the paper platen for each actuation of the ratchet 148, as will be clearly seen by reference to Figs. 1 and 3.

Platen shift.

The type bars are provided with two rows of type faces, one above the other. The lower row of type faces is the row normally used. When it is desired to print from the upper row of type faces a particular group 125 of signals is transmitted for selecting code bar 122, which co-operates with suitable mechanism to raise the paper platen so that

when the type bars are operated the type faces of the upper row will be pressed against the platen. When the bar 122 is selected and permitted to move forward it 5 engages an arm 160 which rocks the supporting rod 161, carrying the arm 162 and moves the pull bar 163 into the path of a reciprocating striker bar 164, which is carried by a bell crank lever operated by a 10 cam on the shaft 48. When the pull bar 163 is operated by the striker bar 164 it rocks the arm 165 which is pivotally supported by the frame of the printer at 166 and elevates the frame 167 which supports the paper 15 platen 145. From Fig. 1 it will be seen that the supporting frame of the platen is supported by parallelogram bars 168 and 169 connected to the frame of the printer in such a manner that the platen will be 20 raised vertically and alignment of the type will not be destroyed. When the arm 160 is moved forward it is held by a suitable pawl 170 (Fig. 3) and consequently the arm 162 and pull bar 163 are locked in their forward 25 positions until the pawl 170 is released. Furthermore, when the arm 162 and pull bar 163 move forward a locking member 171 under the influence of spring 172 is permitted to rotate until the pawl 173 strikes 30 against the extension 174 of the bell crank lever 165, where it is held until the bell crank lever 165 is actuated by a cam on the shaft 48, when the extension 174 is moved back sufficiently to permit the pawl 173 to 35 engage the extension 174, and thereby hold the pull bar 163 in its actuated position. This holding pawl 173 does not engage the extension 174 until the striker bar 164 has moved the pull bar 163 to its extreme down- 40 ward position and consequently has effected a complete shift of the paper platen. Thus, it will be seen that the platen will be held in its shifted position for printing a number of characters from the upper row of 45 type faces until the pull bar 163 is released, which takes place when an unshift signal is transmitted.

Platen unshift.

50 To unshift or return the platen to normal it is only necessary to unlock the mechanism which holds the platen in a shifted position. This is accomplished by transmitting a group of impulses for selecting the code 55 bar 123 which, when permitted to move forward, raises the holding pawl 170 from engagement with the arm 160, as clearly shown in Fig. 3 and permits the arm 162 to return to normal, thereby rotating the member 171 and disengaging the pawl 173 and extension 174. The instant the extension 174 is released, the platen 145, pull bar 163, bell crank lever 165, etc., all return to their 60 normal positions.

Auto signaling.

65

It is desirable that the sending operator should at certain times be able to signal the receiving operator. This may be accomplished by transmitting a group of impulses 70 for selecting the special code bar 121. When the bar 121 is permitted to move forward a pin carried thereby effects the closure of a pair of contacts 181. These contacts may control the ringing of a bell, the lighting 75 of a lamp or any desired signaling means. It is obvious that to operate the signaling means a plurality of times successively the bar 121 may be repeatedly selected, as often as desired. 80

When the special code bars are selected to perform the various mechanical functions hereinbefore mentioned, it is necessary that means be provided to prevent actuation of the type carriage, so that spacing does not 85 take place except when desired. This is taken care of by providing the lever 185 which cooperates with the arm 186 and prevents the actuating pawl 80 from engaging the teeth of the ratchet 81 when any one of 90 the code bars 121 to 125 is selected. The lever 185 is pivotally mounted on the supporting rod 187 and is adapted to be actuated, whenever one of the special code bars moves forward, so that the bent over portion 95 188 is moved under the free end of arm 186 thereby preventing the arm 186 from rotating when the arm 79 is moved forward. When the arm 186 is held against rotation and the arm 79 moves the pawl 80 forward, 100 the pawl rides upon the cam surface 189 and prevents the pawl from engaging the teeth of ratchet 81 and consequently prevents the rotation of shaft 14 and worm-gear 84. 105

In order to prevent operation of the cam shaft except when selecting impulses are being received, a break is provided in the operating circuit of the starting magnet which break is controlled by the latches 25 to 29 inclusive. Whenever any one of the selecting magnets withdraws its respective latch from under a selecting bar it simultaneously closes the circuit contacts 195, thereby preparing the circuit for the starting magnet ready for the sixth or starting 110 impulse. Therefore, the printer can not be operated until at least one positive selecting impulse is received. 115

What is claimed is:

1. In a line printing telegraph receiver 120 the combination of a stationary platen, a type basket comprising a plurality of type bars movable transversely with respect to said platen, and permutation means selectively controlled by line current impulses 125 for controlling the operation of the type bars for line printing.
2. In a printing telegraph receiver for

- line printing the combination of a stationary platen, a traveling carriage comprising a plurality of type bars, a plurality of code bars carried thereby, and mechanism responsive to permutations of line current impulses for controlling the operation of said type bars through the instrumentality of said code bars.
3. In a page printing telegraph receiver, 10 a movable type carriage comprising a plurality of type bars, a stationary paper platen, and mechanism responsive to predetermined groups of line current impulses for selectively controlling the operation of 15 the type bars.
4. In a printing telegraph receiver, a traveling carriage having a plurality of selectable members movable therewith, a plurality of similar stationary selectable members, 20 and means common to all said members for selecting any one of them.
5. In a page printing telegraph receiver, the combination of a stationary platen, a traveling carriage comprising a plurality of 25 type bars and a corresponding number of individually operable code bars, and electro-responsive selecting mechanism controlled by line current impulses and coöperating with said code bars for controlling the operation of said type bars.
6. In a printing telegraph receiver, a stationary printing platen in combination with a type carriage movable transversely with respect to said platen and having a plurality 35 of type bars operable selectively, a plurality of code bars supported by said carriage, and mechanism responsive to line current impulses and coöperating with said code bars to selectively operate said type bars for line 40 printing.
7. In a printing telegraph receiver, a plurality of selecting magnets, a plurality of selecting bars controlled thereby, a plurality of individual permutation bars the selection 45 of any one of which determines the character to be printed, and means for moving said selecting bars transversely of their length to select one of said permutation bars.
8. In a printing telegraph receiver, a plurality 50 of selecting magnets, a selecting bar individual to each of said magnets and controlled thereby, a plurality of individual permutation bars the selection of any one of which determines the character to be 55 printed, and means for moving said selecting bars in a direction at right angle to their length to select one of said permutation bars.
9. In a printing telegraph receiver, a selecting mechanism comprising a plurality 60 of selecting bars normally tending to move, means restraining said bars against movement, selecting magnets for conditioning predetermined ones of said bars for movement, a power shaft, and means operated thereby subsequent to the operation of said 65 magnets for controlling the movement of the conditioned bars and for restoring said bars to normal.
10. In a line printing telegraph receiver, the combination of a stationary printing 70 platen, of a plurality of individually movable printing elements, means for moving said elements in a group longitudinally with respect to said platen, and permutation means acting in response to line current 75 impulses for moving a selected one of said elements into engagement with said platen to print a character.
11. In a printing telegraph receiver, the combination of selecting magnets and an 80 operating magnet, selecting bars normally tending to move and selectively controlled by said selecting magnets, a cam shaft controlled by said operating magnet, means operated by said cam shaft subsequent to the 85 operation of said selecting magnets for permitting the selected ones of said bars to move to their selecting positions simultaneously and for restoring said bars to normal position, and means controlled by said selecting means for printing any desired 90 character.
12. In a printing telegraph receiver, the combination of selecting bars having straight continuous edges, notched members 95 coöperating with the straight continuous edges of said selecting bars and movable singly on the completion of any selection, printing devices controlled by said notched members, and mechanical means for operating 100 said printing devices.
13. In a printing telegraph receiver, the combination of selecting bars and printing devices, code bars having notched edges coöperating with said selecting bars and movable in a direction longitudinal thereof, levers suspended from said printing devices, and means controlled by the movement of the code bars and coöperating with said levers for controlling the operation of the 110 printing devices.
14. In a page printing telegraph receiver, a movable type carriage comprising a plurality of type bars, a stationary paper platen, a rotatable cam shaft, and means 115 controlled by said cam shaft and coöperating with said type bars for effecting the printing of a desired character.
15. In a printing telegraph receiver, selecting means normally tending to move, a plurality 120 of restraining means holding said selecting means against movement, means controlled by line current impulses for withdrawing one of said restraining means from said selecting means, a rotatable cam shaft, 125 and means controlled by said cam shaft for withdrawing the other of said restraining means, whereby said selecting means may

move to their selecting position and for restoring said selecting means to normal position.

16. In a printing telegraph receiver, a rotatable shaft normally tending to rotate, line controlled means for releasing said shaft, means controlled by said shaft for effecting the selection and printing of any desired character, and a friction-brake controlled by the rotation of said shaft for stopping it at the end of each revolution.

17. In a printing telegraph receiver, a movable type carriage, comprising a plurality of printing bars, a rotatable cam shaft, and means controlled by said shaft for moving the type carriage step by step for the printing of each character.

18. In a printing telegraph receiver, a movable type carriage including selectively operable type bars, a rotatable cam shaft, means controlled by said shaft for stepping the type carriage forward when each type bar is operated, and means controlled by said cam shaft for permitting the return of the type carriage to its initial position.

19. In a printing telegraph receiver, a movable carriage comprising a plurality of type levers, a toothed rack, a cam shaft, a pinion coöperating with the toothed rack and actuated by said cam shaft for moving said carriage in one direction step by step, and means for moving the carriage in the opposite direction to its initial position in one operation.

20. Printing telegraph apparatus, comprising a traveling carriage, a rack, a worm-gear coöperating with said rack for advancing the carriage, means for withdrawing the rack from engagement with the worm-gear to permit the return of said carriage, means for holding the rack in its actuated position during the return of the carriage, and means actuated by the carriage upon its return for releasing said holding means.

21. In a printing telegraph receiver, a stationary paper platen, selecting mechanism, a plurality of type levers responsive to said selecting mechanism and coöperating with said paper platen for printing any desired character, and means for placing said selecting mechanism in readiness for the selection of a character before the printing of the preceding character selected thereby is completed.

22. In a page printing telegraph receiver, selecting mechanism responsive to line current impulses, type bar printing mechanism controlled thereby and movable transversely with respect to said selecting mechanism, and means whereby a new character may be selected before the printing of the preceding character selected is completed.

23. In a line printing telegraph receiver, selecting mechanism responsive to line current impulses, printing means responsive to

said selecting mechanism, means for moving said printing means in a direction transverse with respect to said selecting mechanism, and means whereby said selecting mechanism can select a new character before the printing of the preceding character selected thereby is completed.

24. In a printing telegraph receiver, a plurality of selecting members normally retained against movement, means responsive to a set of line current impulses for selectively releasing said members, means for restoring said members, and means operating on the receipt of a second set of line impulses before the complete restoration of said members to lock said releasing means in their selected positions.

25. In a printing telegraph receiver, a plurality of selecting members, means responsive to a set of line current impulses for selectively releasing said members, means for restoring said members, means operating on the receipt of a second set of line impulses before the complete restoration of said members to lock said releasing means in their selected positions, and means for releasing said locking means.

26. In a printing telegraph receiver, selecting mechanism, comprising a plurality of selecting bars, a latch individual to each of said bars and normally in engagement therewith, means for withdrawing said latches from engagement with said selecting bars, means for holding said latches out of engagement with said bars, and means for releasing said holding means.

27. In a printing telegraph receiver, selecting mechanism, comprising a plurality of selecting bars, a latch normally in engagement with each of said bars, means controlled by line current impulses for withdrawing said latches from engagement with said selecting bars, means for holding said latches out of engagement with said bars and means for releasing said holding means.

28. In a printing telegraph receiver, a selecting mechanism, comprising a plurality of selecting bars movable in a direction transversely of their length, latches for holding said bars in their normal positions, means for withdrawing said latches to permit actuation of said selecting bars, and means for restoring said selecting bars to normal.

29. In a printing telegraph receiver, selecting mechanism, comprising a plurality of selecting magnets, a plurality of selecting bars, a plurality of latches normally in engagement with said selecting bars and arranged to be actuated by said selecting magnets, means for holding said latches out of engagement with said selecting bars, and means for withdrawing said holding means from said latches.

30. Printing telegraph apparatus com-

prising a paper platen, a support therefor, a rocker arm in engagement with said support, a member freely suspended from and supported by said rocker arm, a rotatable 5 cam shaft, means actuated by said shaft and adapted to engage said member for shifting the platen, means for holding the platen in its shifted position, and means controlled by a special group of impulses for releasing 10 said holding means.

31. Printing telegraph apparatus, comprising a rotatable shaft, a spring for rotating said shaft, an intermittently operating motor for controlling the tension of said 15 spring, means controlled by said shaft for causing the intermittent operation of said motor, and a clutch for preventing counter rotation of said motor.

32. Printing telegraph apparatus, comprising a rotatable cam shaft, a spring for driving said shaft, an intermittently operating motor for winding said spring, circuit connections for said motor, and a traveling nut actuated by said cam shaft for 25 controlling the circuit connections of said motor.

33. Printing telegraph apparatus, comprising an intermittently operating motor, circuit connections therefor, a shaft, means 30 connecting the shaft and the motor, means actuated by the rotation of said shaft for controlling the circuit connections of the motor, and means for preventing counter rotation of said motor.

34. Printing telegraph apparatus, comprising a rotatable shaft, driving means for said shaft, line controlled means for rendering said driving means effective, a reciprocating member supported by said shaft for 40 controlling the driving means, and a clutch for preventing backward rotation of said driving means.

35. Printing telegraph apparatus, comprising a cam shaft normally tending to rotate, means for releasing said shaft, and a brake-band controlled by said shaft and co-operating therewith to stop the rotation of said shaft at the end of each revolution.

36. Printing telegraph apparatus, comprising a rotatable shaft, means for driving said shaft, a friction-brake for controlling the rotation of said shaft, a magnet for releasing the brake, and means carried by said shaft for controlling the operation of 55 said driving means.

37. Printing telegraph apparatus, comprising a rotatable shaft, means for driving the said shaft, a friction-brake for holding said shaft against rotation, a magnet for 60 releasing said brake, and means actuated by the shaft for controlling the operation of the driving means.

38. Printing telegraph apparatus, comprising a cam shaft normally tending to rotate, a brake-band for holding said shaft

against rotation, a toggle-joint for releasing said brake-band instantaneously, an electromagnet controlled by line current impulses for actuating said toggle-joint, and cams carried by said shaft and co-operating with 70 said brake-band for stopping the rotation of said shaft.

39. Printing telegraph apparatus, comprising a shaft normally tending to rotate, a brake-band for holding said shaft against 75 rotation, a toggle-joint for releasing said brake-band when actuated, an electromagnet for actuating said toggle-joint, and cams carried by said shaft and co-operating with 80 said toggle-joint and said brake-band for stopping the rotation of the cam shaft at the end of each revolution.

40. Printing telegraph apparatus, comprising a rotatable shaft, a brake-band for holding said shaft against rotation, means 85 for releasing said brake-band, and cams carried by said shaft and co-operating with said brake-band for stopping the rotation of said shaft at the end of each revolution.

41. In a printing telegraph receiver, a 90 traveling carriage having a plurality of selectable members movable therewith, a plurality of stationary selectable members, means common to all said members for selecting any one of them, means acting on 95 the selection of one of said movable members to advance the carriage, and means operating on the selection of one of said stationary selecting members to prevent the advance of said carriage.

42. In a printing telegraph receiver, a traveling carriage having a plurality of selectable bars movable therewith, a plurality of stationary selectable bars, means common to all said bars for selecting any one of 105 them, means acting on the selection of one of said movable bars to advance the carriage, and means operating on the selection of a particular one of said stationary bars to return the said carriage to normal.

43. In a printing telegraph receiver, the combination of a traveling type carriage, comprising a plurality of character arms, a selectable member individual to each character arm, and an actuating arm, with stationary selecting bars co-operating with said selectable members to select one of said character arms, and a striker bar common to all said selectable members and co-operating with said actuating arm to actuate the character 115 arm selected.

44. In a printing telegraph receiver, selecting mechanism comprising a plurality of selecting magnets, selecting bars controlled thereby, code bars co-operating with said selecting bars, a rotatable cam shaft, means controlled by said cam shaft for releasing the selected code bar, and means controlled by said shaft and selected code bar for printing any desired character.

45. In a printing telegraph receiver, selecting bars, means for selectively releasing said bars, a cam shaft controlling the movement of the released bars, code bars coöperating with said selecting bars, and a printing bar controlled by said cam shaft and co-operating with said code bars for effecting the printing of characters.
46. In a printing telegraph receiver, selecting bars normally tending to move, means controlled by line current impulses for conditioning the selecting bars for movement, a rotatable cam shaft also controlled by line current impulses, and means controlled by said cam shaft for actuating the selecting bars.
47. In a printing telegraph receiver, a rotatable cam shaft, a movable type carriage comprising a plurality of printing elements, code bars coöperating with said printing elements and carried by said type carriage, and means controlled by said code bars and actuated by said cam shaft to effect the actuation of said printing elements.
48. In a printing telegraph receiver, the combination of a movable type carriage, printing elements carried thereby, means for moving said type carriage, a plurality of selectable code bars, means for causing the selected code bars to control the printing elements, and means coöperating with the code bars for actuating the printing elements to print a desired character.
49. Printing telegraph apparatus, comprising a traveling type carriage, a rack, a worm-gear traveling with said carriage and coöperating with said rack for advancing the carriage step by step, means for withdrawing the rack from engagement with the worm-gear to permit the return of said carriage, and means actuated by the carriage upon its return to permit the said rack to re-engage the worm-gear.
50. In a printing telegraph receiver, selecting mechanism comprising a plurality of selecting bars normally tending to move, a latch individual to each of said bars and normally in engagement therewith to prevent movement thereof, means for withdrawing said latches from engagement with said selecting bars, additional means normally in engagement with said bars to prevent actuation thereof when said latches are withdrawn, a cam shaft, and means actuated thereby to control said additional means whereby said selecting bars may be actuated in accordance with the respective latches withdrawn.
51. In a printing telegraph receiver, a rotatable cam shaft, selecting bars, means controlled by line current impulses for selectively conditioning said bars for movement, a plurality of code bars controlled by said selecting bars, means for normally holding said code bars out of engagement with said selecting bars, and means controlled by said cam shaft for releasing the conditioned ones of said selecting bars and for releasing the selected code bar.
- In witness whereof, I hereunto subscribe my name this 5th day of June, A. D. 1917.
- HARRY PFANNENSTIEHL.
